INVENTOR:

David E. Turner,
By H.M. Richards, atty.

UNITED STATES PATENT OFFICE.

DAVID E. TURNER, OF GALESBURG, ILLINOIS.

MOLDER'S SHIFT-BOX.

1,201,394.

Specification of Letters Patent. Patented Oct. 17, 1916.

Application filed February 18, 1916. Serial No. 79,104.

To all whom it may concern:

Be it known that I, DAVID E. TURNER, a subject of the King of Sweden, and a resident of Galesburg, in the county of Knox and State of Illinois, have invented a new and useful Molder's Shift-Box, of which the following is a specification.

In casting or molding metals, nearly all foundries employ snap-flasks for making the relatively small articles. When the mold 10 has been completed it is carried, while within the snap-flask, to its position on the floor, whereupon the snap-flask is removed and a shift-flask or box set down snugly upon the mold. It is extremely essential that the latter fit the mold accurately, in order, primarily, to preserve its shape exactly as it was when the snap-flask was removed, whereby the shape of the cavity is left undisturbed. Again, in order that the gases 15 may not escape the shift-box must fit with precision. Quite frequently the molten metal will, as the casting is being poured, escape and run out onto a side or an end of the shift-box, and if these are of wood the 20 box or a portion thereof will be so burned that the box will be rendered useless. If the box is made of sheets, or even of a single piece of metal, non-separable, the molten 25 metal will either burn a hole therein or adhere thereto, thus utterly destroying the utility thereof. These shift-boxes have heretofore been made to conform to standard sizes of snap-flasks, thus necessitating the 30 carrying of a large number in order to have a sufficient quantity to apply to a large number of varying sizes of molds.

In view of the foregoing the principal object of my invention is to provide a shift-box the dimensions of which are variable or 35 adjustable laterally, longitudinally and vertically, whereby to fit molds differing in size, in shape, or in both.

Another object is to provide a shift-box 40 made of a plurality of independent sections any of which, should a hole be burned through it, or should a lump of metal, in cooling, adhere to it, may be quickly and easily removed and another one substituted 45 therefor.

Other objects will presently appear. Some of these will be obvious and others particularly pointed out.

The invention consists, substantially, in 50 the improvements hereinafter described.

In the accompanying drawings, which

illustrate a preferred embodiment of my invention: Figure 1 is a perspective of a shift-box assembled in flared or tapered form; Fig. 2, a side elevation, showing by dotted lines two of the adjustments; Fig. 3, an end view; Fig. 4, a similar view, another adjustment being here illustrated; Fig. 5, a detail showing the manner of applying an additional or supplemental piece, whereby the 60 shift-box may be made to fit molds of unusual depth; and Fig. 6, a detail of one of the ends.

Coming now to a detailed description of the drawings, and referring to the elements and, where necessary, to the parts thereof, each by a distinguishing numeral, uniformly employed, 2, 2' indicate sides each of which has a lower flange 3 and an upper flange 3', the latter provided with apertures 4, the 65 body portion of each side being provided near each of its corners with a slot 5.

6, 6' indicate ends each of which is provided at its upper edge with a flange 7 having apertures 8; at one of its ends with a flange 9 having apertures 10 adapted for registration each with the adjacent slot 5; and near the other edge with an aperture 11, as shown best in Fig. 6.

12, 12' indicate supplemental ends or fillers each of which has at its outer edge a flange 13 provided with apertures adapted to register each with the adjacent slot 5. 75 15, 15 designate slots adapted to register each with the adjacent aperture 11.

16 (Fig. 5) indicates an extension which may be used when the shift-box is not sufficiently deep to receive and bind a mold of unusual height. These extensions may be of any suitable material and secured to each side and each end in any suitable manner, the one shown having a flange 17 provided with apertures registering with those in the flange 3' of the side 2' and secured thereto by bolts 18 and nuts 19.

20, 20' designate bolts each of which passes through a slot 15 and through the aperture 11 registering therewith, and 21, 21 indicate nuts engaged one with each of said bolts.

22, 22 designate bolts each of which passes through an aperture in a flange 13 and through the adjacent registering slot 5, and 23, 23 indicate nuts, each engaged with one of said bolts.

24, 24 indicate bolts each passing through a slot 5 and the registering aperture 10, and

25, 25 designate nuts each of which engages one of said bolts.

The sizes of the snap-flasks being known, the shift-box may, by means of the slots, 5 apertures, bolts, nuts and supplemental ends, be adjusted to correspond in dimensions and shape practically exactly therewith, in order that it may snugly fit the mold when the latter has been laid on the floor and the snap-flask removed. The ends 6, 6' are of such sizes as to normally fit molds of standard 10 dimensions, but when the molds are of unusual or uncommon size, wider than the ordinary ones, the supplemental ends or fillers 15 completely fill the gap which otherwise would appear.

It will be seen that my improved box may be made to fit molds differing in either their lateral or their longitudinal dimensions or 20 in both, and may be beveled or flared, whereby it may be quickly and accurately adjusted to fit a vast number of variously shaped and dimensioned molds.

Having thus described my invention I 25 claim as new the following, to-wit:—

1. In a box, a pair of sides, a pair of ends each of which has a flange at one of its edges, means for adjustably connecting the flange of each of said ends with one of said sides, 30 and fillers, both adjustably connected with the other of said sides and each with one of said ends.

2. In a box, a pair of sides each of which has at its upper edge a flange and each flange provided with apertures; a pair of 35 ends each of which has at its upper edge a flange and each flange provided with apertures, means for adjustably connecting said

ends with one of said sides, and fillers for adjustably connecting said ends with the other of said sides.

3. A shift-box comprising sides and ends, a plurality of means whereby either of said sides may be adjusted either parallel with or divergent from the other, said means including L-shaped supplemental ends adapted to coöperate with said ends and sides whereby to alter either the length or the breadth of the box, said plurality of means adapted also for adjusting the ends and 45 supplemental ends whereby to change their inclinations.

4. In a box, a pair of sides plane throughout their lengths, a pair of ends proper each of which has a rectangularly turned flange, 55 both of said flanges resting against the same one of said sides, bolts adjustably connecting said flanges with said sides, means for locking the bolts, and a pair of L-shaped supplemental ends one limb of each of which is adjustably connected with the adjacent end proper and the other limb of which is adjustably connected with the other side.

5. A shift-box comprising sides, ends proper and supplemental ends, means for 65 adjusting said sides toward or from each other and for inclining them with relation to each other, said means adapted also for adjusting and locking said ends proper and supplemental ends to correspond to any or 70 all of the adjustments of the sides.

In testimony that I claim the foregoing as my sole invention I hereto subscribe my name at Galesburg, in the county and State aforesaid, this 11th day of February, 1916. 75

DAVID E. TURNER.
